UNITED STATES PATENT OFFICE.

EDMOND BIRD COSBY, OF ROGERS, TEXAS.

DESIGN FOR A SMOOTHING-IRON.

SPECIFICATION forming part of Design No. 18,694, dated October 23, 1888.

Application filed August 22, 1888. Serial No. 283,476. Term of patent 14 years.

To all whom it may concern:

Be it known that I, EDMOND BIRD COSBY, of Rogers, in the county of Bell and State of Texas, have invented a certain new and useful 5 Design for Smoothing-Irons; and I do hereby declare, the following to be a full, clear, and exact description of the invention, such as will enable others skilled in the art to which it pertains to make and use it, reference be-
to ing had to the accompanying drawing, which forms part of this specification.

My invention relates to a design for smoothing-irons; and it consists in the representation of a locomotive upon the top of the body of 15 the iron, so as to give the iron a more pleasing and attractive appearance, as will be more fully described hereinafter.

The accompanying drawing represents a side elevation of an iron which embodies my 20 invention.

A represents the body of the iron, which may be of the usual shape. Upon the top of

this body is the representation of a locomotive, C, provided with a cab, D. The handle G extends from the smoke-stack H to the cab, 25 and this handle is grooved and shaped so as to represent the smoke which is issuing from the smoke-stack.

The whole design presents a pleasing and attractive appearance, and adds greatly to the 30 beauty of the iron.

Having thus described my invention, I claim—

A design for a smoothing-iron, consisting of the representation of a locomotive upon the top 35 of the iron, and having the handle representing smoke, substantially as shown and described.

In testimony whereof I affix my signature in presence of two witnesses.

EDMOND BIRD COSBY.
